Attorney

UNITED STATES PATENT OFFICE.

JACOB JONES, OF SEATTLE, WASHINGTON.

SOUND REPRODUCER.

Application filed May 1, 1920. Serial No. 373,214.

To all whom it may concern:

Be it known that I, JACOB JONES, a citizen of the United States, residing at Seattle, in the county of King and State of Washington, have invented certain new and useful Improvements in Sound Reproducers, of which the following is a specification, reference being had to the accompanying drawings.

10 This invention relates to sound reproducers, and particularly to a sound reproducer for use in connection with phonographs.

An object of the invention is to provide a reproducer which reproducer sounds in a clear tone and at the same time eliminates scratching and other harsh sounds caused by the engagement of the stylus with the record.

Another object is to provide a reproducer of this character which reproduces a true tone without harsh sounds, at all times regardless of the speed of the machine.

Still another object is to provide a reproducer of this character including a diaphragm which receives the sound from a member that is engaged with but not secured to the diaphragm.

A further object is to provide a reproducer including a diaphragm which is disposed between pneumatic gaskets which serve to absorb false sounds.

A still further object is to provide a reproducer of this character including a stylus carrying arm, one end of which is provided with a sound transmitting member, the portion of the stylus carrying arm adjacent the sound transmitting member being reduced and resilient to serve as a spring in forcing the sound transmitting member against the diaphragm.

40 With these and other objects in view the invention consists in the improved construction and arrangement of parts to be herein-after more particularly described, fully claimed and illustrated in the accompanying drawings, in which:

Figure 1 is a vertical elevation of a sound reproducer constructed in accordance with an embodiment of the invention;

Figure 2 is a transverse sectional view 50 showing the pneumatic gaskets and the sound transmitting member;

Figure 3 is a fragmentary and sectional view of one of the pneumatic gaskets and its air inlet member.

55 Referring to the drawings, 5 designates a reproducer sound box having a pair of an-

nular grooves 6 in the inner surface of its peripheral flange 7. A diaphragm 8 is mounted in the sound box between the groove 6 and it is held in position by means of pneumatic gaskets 9. Each of the gaskets 9 is tubular in formation and is provided with an inlet member 10 in which a spring pressed valve 11 is disposed, a cap 12 being provided to close the outlet. By this means a suitable pump may be attached to the inlet to inflate the gaskets, the inflation of the gaskets causing the same to firmly engage the diaphragm on both sides thereof and securely hold the same in position without causing the diaphragm to be penetrated by any fastening means or engaged by metal parts so that false or scratching sounds transmitted to the diaphragm are absorbed by the pneumatic gaskets.

The sound box 5 is provided with ears 13 between which trunnions 14 of a stylus carrying arm 15 are mounted. These trunnions are engaged by the usual screws 16 so that they may be adjusted to the tension desired. The stylus carrying arm 15 is provided on one end with the usual stylus receiving socket 17 and has its other end portion 18 reduced and curved outwardly as at 19 and then extended inwardly and upwardly, the extremity 20 extending in alignment with the main portion of the arm.

By extending the portion 19 outwardly and reducing the same, a spring action is afforded, the purpose of which will be hereinafter described.

In order to transmit the sound received by the stylus arm to the diaphragm without causing the diaphragm to engage any metal part, or to cause the formation of openings in the diaphragm, a sound transmitting member 21 is provided. This member is preferably constructed from cork, is circular in formation and has extending from the central portion of its side 22 a socket member 23 having a bore 24 adapted to receive the end 20 of the stylus carrying arm, a set screw 24^a being threaded into the socket for engagement with the end 20 to prevent disengagement of the sound transmitting member from the stylus carrying arm. The side 25 of the sound transmitting member 21 is concave so as to permit the marginal edges 26 to engage the diaphragm, and at the same time the concavity of the side 25 provides a chamber through which

the sound may pass on to the diaphragm in addition to being transmitted by the marginal edges 26.

To further assist the stylus carrying arm 5 in forcing the sound transmitting member 21 against the diaphragm, a spring or like yieldable member 27 is provided and has its end 28 soldered or otherwise secured to the sound box adjacent or between the ears 13. 10 The end 29 of the spring is extended outwardly between the ears, over one of the trunnions 14 into engagement with the stylus carrying arm 15 above the pivot of the stylus arm. This spring is of the compression type so that it constantly forces the stylus carrying arm 15 toward the diaphragm and thus causes the sound transmitting member 21 to engage the diaphragm 15 at all times.

It is a well known fact that metal used in the construction of amplifiers and sound reproducers is largely responsible for the harsh and grating sounds transmitted to the stylus. At the same time, however, metal 25 is necessary in order to render the device substantial. With the sound transmitting member 21, strength is provided at the same time all metal connections are eliminated. This is possible by providing a concavity in 30 one surface of the sound transmitting member so as to not only prevent the escape of sound, but also to permit the sound to be transmitted by the marginal edges of said surface to the diaphragm, but in order to 35 transmit sounds to the diaphragm the sound transmitter must be firmly engaged with the diaphragm. This is accomplished by means of the resilient reduced end portion

18 of the stylus carrying arm and the compression spring 27, which causes the sound transmitting member to be constantly forced into engagement with the diaphragm. 40 In this way, the sound transmitting member coacts with the diaphragm regardless of the flexing of the diaphragm by the sound vibrations transmitted thereto. In addition to this, the marginal edges of the diaphragm are not secured by any metal means, but are disposed between pneumatic gaskets which serve to absorb any harsh sounds 45 that might be transmitted by the member 21. By this novel arrangement only the true tone or sound is transmitted to the diaphragm so that the natural sound of the voice is reproduced without harsh or false 50 sounds.

The invention having been set forth, what is claimed as new and useful is:—

Sound transmitting means for a sound reproducer embodying a diaphragm, a 60 mounting therefor, a stylus carrier pivoted at its lower end portion to the mounting, a spring carried by and extending upwardly from beneath the mounting and engaged with the central portion of the stylus carrier for urging the upper end portion of said stylus carrier toward the diaphragm, a sound transmitting member, a socket member threaded in the outer face of said sound transmitting member and arranged 65 to receive the upper end portion of the stylus carrier.

In testimony whereof I hereunto affix my signature.

JACOB JONES.
